UNITED STATES PATENT OFFICE.

FREDERIC W. HARJES, OF TICONIC, IOWA.

ELEVATOR.

1,109,062.

Specification of Letters Patent.

Patented Sept. 1, 1914.

Application filed January 31, 1914. Serial No. 815,728.

To all whom it may concern:

Be it known that I, FREDERIC W. HARJES, a citizen of the United States, residing at Ticonic, in the county of Monona and State 5 of Iowa, have invented certain new and useful Improvements in Elevators, of which the following is a specification, reference being had to the accompanying drawings.

This invention relates to elevators and has 10 relation more particularly to a device of this general character especially designed and adapted for use in connection with a binder; and the object of the invention is to provide a device of this general character 15 having novel and improved means whereby the grain, after being cut, topples back upon the elevator and is properly conveyed to the binder or other desired locality.

The invention consists in the details of 20 construction and in the combination and arrangement of the several parts of my improved elevator whereby certain important advantages are attained and the device is rendered simpler, less expensive and otherwise 25 more convenient and advantageous for use, all as will be hereinafter more fully set forth.

The novel features of the invention will 30 be carefully defined in the appended claim. In order that my invention may be the better understood, I will now proceed to describe the same with reference to the accompanying drawings, wherein—

Figure 1 is a view in top plan of an elevator 35 constructed in accordance with an embodiment of my invention; Fig. 2 is a view in side elevation of the device as illustrated in Fig. 1; Fig. 3 is a sectional view taken substantially on the line 3—3 of Fig. 1; Fig. 4 is a sectional view taken substantially 40 on the line 4—4 of Fig. 1; Fig. 5 is a perspective view, detached, of the floating plate, as included in the present embodiment of my invention; Fig. 6 is a perspective view, 45 detached, of a guide member for the floating plate; Fig. 7 is a sectional view taken substantially on the line 7—7 of Fig. 2; and Fig. 8 is a sectional view taken substantially on the line 8—8 of Fig. 1.

As disclosed in the accompanying drawings, 50 1 denotes a horizontally disposed frame substantially inclosed and having its bottom 2 detachable so that access within the frame may be had with convenience and facility as the occasion may require and especially for the purposes of repairing any

of the parts of the mechanism contained therein as will hereinafter be more particularly referred to. Suitably connected with the forward longitudinal side of the frame 60 is the sickle or cutting mechanism 3. As this mechanism 3 in its detail forms no particular part of my present invention, a specific illustration and description thereof is believed to be unnecessary as the same may be 65 constructed and operated in any manner desired.

Operatively supported by the side walls 4 of the frame 1 and adjacent the opposite ends of such frame are the shafts 5 having affixed thereto in close proximity to the side walls 4, the sprockets 6 around which are directed the endless chains 7 connected by the cross rods 8. The rods 8 are provided with the carrying lugs 9 and the position 70 of the upper stretches of the chains 7 relative to the top plate 10 of the frame 1 is such as to permit the lugs 9 to project through the elongated slots 11 produced in such top plate 10 and extend a predetermined distance thereabove so that grain toppling back upon the frame 1, after being severed by the cutting mechanism or sickle 3, will be carried toward the upwardly directed or inclined frame 12, to be herein-after more particularly referred to. The frame 12 is also substantially inclosed and has its lower marginal portions in overlapping relation with the adjacent marginal 75 portions of the frame 1, and suitably secured thereto, as indicated at 14 in Fig. 3. The frame 1, adjacent its opposite ends, has operatively supported by the side walls 15, the transverse shafts 16 having affixed thereto in close proximity to the side walls 15 the sprocket wheels 17 around which are 80 directed the chains 18, the upper stretches of which are in close proximity to the top plate 19. The chains 18 are connected by the cross rods 20 from which project the carrying lugs 21 which extend through the slots 22 produced in such top plate 20 and being adapted to properly engage the severed grain and carry the same up to the binder. As the binder forms no part of 85 the present invention, the same is omitted, except a fragment 23 to indicate a connection between the frame 12 and the binder. The uppermost shaft 16 is operatively connected, as at 24, with a movable part of the 90 binder, while the adjacent shafts 16 and 5 are operatively connected, as indicated at 95

25, whereby it will be readily perceived that requisite movement to the chains 7 and 18 may be effected.

Coacting with the frame 12 and disposed above the top 19 thereof and in substantial parallelism therewith is the floating top 26 formed preferably of metal and freely capable of movement relatively to the top 19 as determined by the quantity of grain being carried upwardly by the lugs 21. As herein disclosed, the side marginal portions of the top 26 have depending therefrom the elongated arms 27 provided at their upper extremities with the angular extensions 28, whereby the same may be suitably anchored to the upper surface of the floating top 26. The arms 27 are adapted to have sliding engagement with the vertically disposed guide-ways 29, suitably affixed to the side walls 15 of the frame 12 whereby it will be readily perceived that the floating top 26 is operatively maintained in requisite position. I also find it of advantage to have the lower marginal edge of the floating top 26 turned back on a predetermined curve, as indicated at 30, whereby proper passage of the grain beneath such top 26 is assured, while the opposite end portion of the floating top 26 is disposed on a downward curve, as indicated at 31, to assure proper delivery of the grain to the binder. I also find it of advantage to provide the free end of the frame 1 with the upwardly and outwardly directed transverse plate or wall 32 which assures the toppling grain to fall upon the top plate 10 of the frame.

In the accompanying drawings, I have illustrated only the essential features of my invention and it will be readily perceived that in order to overcome various disadvan-

tages and to make the device wholly operative, other parts may need to be employed but as such parts form no part of my present invention, they have been omitted in order not to obscure my present invention.

From the foregoing description, it is thought to be obvious that an elevator constructed in accordance with an embodiment of my invention is of an extremely simple and comparatively inexpensive nature and is particularly well adapted for use by reason of the convenience and facility with which it may be assembled and operated and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A device of the class described including a substantially inclosed frame having a substantially horizontal portion, and an inclined portion, guide members arranged upon the sides of the inclined portion of the frame and arranged in spaced relation, a top having the lower end upturned and the other end downturned, supporting arms secured to the longitudinal edges of the top adapted to be removably arranged within the guide members to hold the top in position.

In testimony whereof I hereunto affix my signature in the presence of two witnesses.

FRED. W. HARJES.
